CLAIM

The ornamental design for a pair of bluetooth headphones, as shown and described.

DESCRIPTION

FIG. 1 is a front view of a pair of bluetooth headphones showing my new design;
 FIG. 2 is a rear view thereof;
 FIG. 3 is a left view thereof;
 FIG. 4 is a right view thereof;
 FIG. 5 is a top view thereof;
 FIG. 6 is a bottom view thereof; and,
 FIG. 7 is a perspective view thereof.
